Marilyn I. Horecny, Seaside, Oreg.

Application April 2, 1954, Serial No. 29,826

Term of patent 7 years

(Cl. D92—1)

To all whom it may concern:

Be it known that I, Marilyn I. Horecny, a citizen of the United States, residing at Seaside, in the county of Clatsop and State of Oregon, have invented a new, original, and ornamental Design for a Textile Fabric or Similar Article, of which the following is a specification, reference being had to the accompanying drawing, forming part thereof.

The single drawing figure is a plan view of a section of a textile fabric or similar article, showing my new design.

The design is repeated as shown, over the entire surface of the material.

I claim:

The ornamental design for a textile fabric or similar article, as shown and described.
